UNITED STATES PATENT OFFICE.

BENJAMIN M. DES JARDINS, OF HARTFORD, CONNECTICUT, ASSIGNOR, BY MESNE ASSIGNMENTS, TO UNION TYPEWRITER COMPANY, OF JERSEY CITY, NEW JERSEY, A CORPORATION OF NEW JERSEY.

TABULATING MECHANISM FOR TYPE-WRITING MACHINES.

No. 926,716.

Specification of Letters Patent.

Patented June 29, 1909.

Original application filed July 10, 1899, Serial No. 723,390. Divided and this application filed October 1, 1904, Serial No. 226,784. Renewed March 24, 1908. Serial No. 422,963.

To all whom it may concern:

Be it known that I, BENJAMIN M. DES JARDINS, citizen of the United States, and resident of Hartford, in the county of Hartford 5 and State of Connecticut, have invented certain new and useful Improvements in Tabulating Mechanism for Type - Writing Machines, of which the following is a specification.

10 My invention relates to typewriting machines and more especially to tabulator mechanism for such machines.

The tabulating device herein described includes means for quickly setting a typewriter carriage at any point on the scale for the purpose of locating the first letter or figure of a line forming part of a column.

15 My invention consists in certain features of construction and combinations and arrangements of parts which will be fully set forth herein and particularly pointed out in the claims.

The present case is a division of my application, Serial No. 723,390, filed July 10th, 25 1899, for Letters Patent for adding and computing attachment for typewriters.

My invention is illustrated in the accompanying drawings, in which,

Figure 1 is a plan view of the improvements and so much of an ordinary typewriter as is necessary to illustrate the application thereto of the present invention; Fig. 2 is a right-side elevation of the same shown partly in section; Fig. 3 is a left-hand view of the typewriter carriage shown in Fig. 1 and the devices supported thereon; Fig. 4 is a front view of the part shown in Fig. 3; Fig. 5 is a front view of the right-hand upper portion of the parts shown in Fig. 1; and Fig. 6 is a 40 front view of the keyboard shown in the lower part of Fig. 1.

My tabulator mechanism may be applied to any ordinary typewriting machine. The machine, a portion of which is shown in the drawings, comprises a main frame having a base portion 1, from which rise posts 2, which support a top plate 3. The platen 4 is mounted on a carriage which is so mounted on the machine as to have a motion transversely thereto. The particular means whereby the carriage is so mounted are immaterial to my invention and have not been shown

herein. Said carriage may be drawn across the machine by any suitable power device such as the spring drum and connections ordinarily used in such machines, and the motion of said carriage may be controlled by the usual or any suitable step by step feed mechanism.

The particular tabulator mechanism shown in the present case is used in connection with a computer having a casing 5; but my invention is not limited to such use. Said tabulating mechanism comprises a keyboard 6 having a series of keys 7 suitably marked. 60 Each of these keys is mounted on a key lever 8 having a toe 9 which is thrust out when the key is depressed to engage a stop 10 on the frame of the computer to limit the downward movement of said lever. When the 70 key 7 is depressed its lever is first rocked to throw the toe 9 to position over its stop 10 and then the entire keyboard 6 is carried down, said keyboard being mounted on arms 11 pivoted on a shaft 12 of the computing 75 mechanism. The stops 10 are stepped as shown in Fig. 6. It will be perceived that each key has an independent initial movement during which it does not affect the keyboard 6 and the parts controlled thereby, 80 and also a final movement during which it operates said parts, and that the extent of this final movement is different for each key, so that the keyboard is operated different distances by the different keys. A link 13 85 connects one of the arms 11 with a sector-gear 14 which meshes with a pinion 15 on a rock shaft 16. The shaft 16 has on its upper end a pinion 17 which meshes with a rack 18 and said rack in turn meshes with a pinion 19 90 on a shaft or stop rod 20 mounted in bearings in the upper part of the typewriter frame adjacent to the carriage. On the shaft 20 are ten radial pins 21 uniformly stepped about the shaft and spaced longitudinally on the shaft at distances apart equal to the units of the typewriter scale. The stepped pins 21 constitute one set of tabulating stops.

Above the shaft 20 and carried in bearings 100 on the usual typewriter carriage (indicated at 22, Fig. 3) is a shaft 23 having a series of pins 24 radially arranged and uniformly spaced about its circumference, the said pins

being separated longitudinally by amounts which equal ten units of the typewriter scale. The shaft 23 has a beveled gear 25 which meshes with a segment 26. The segment 26 is carried by a rock shaft 27 and on the opposite side of the rock shaft is an arm or blade 28 which is engaged by the stems of a series of keys 29. The plate 28 is tapered and the shaft 27 is inclined to the row of keys 29 as viewed from above (see Fig. 1) so that the keys operate on the blade at different distances from the shaft. Each of these keys corresponds to ten units on the typewriter scale and is adapted to render its corresponding stop pin 24 operative. The stop pins 24 may be termed column stops and the stop pins 21 denominational stops. The typewriter carriage is located for the beginning of a number or word at any part of the scale by depressing a key 29 corresponding to the section of ten units in which the number or word is to be begun and depressing one of the keys 7 to locate the particular unit in the section of ten units. The key 7, through the connections described, rocks the shaft 20 and locates the proper pin 21 in position to engage the pin 24 which is selected by the key 29. While the two keys are depressed the carriage is moved until the two selected pins are in contact. The parts thus adjusted bring the first figure of a number or the first letter to be written in the desired position. If, for instance, it is desired to begin with the graduation 54 on the typewriter scale, the key 29 marked 5, and the fourth key from the right of the keyboard 6 would be depressed and the carriage then moved until it was intercepted by the selected pins 21, 24.

In the arrangement shown the stops 21 are situated at different distances from the path of the stop or part of the carriage which they are to engage, and each occupies, one after the other, the same number of degrees, (or angle) around the axis of the stop carrier, so that the required turning of the carrier from any one stop to the next is always of a certain angle or amount, and the required turning of said carrier from its normal position to different stops is of different amounts or distances.

As shown in Figs. 2 and 5, the series of stops 21 does not extend entirely around the shaft 20, but said stops are segmentally arranged about said shaft, an angular space being left between the end stops of the series. There is also an angular space between each stop and the stop next to it in the series. These intervening spaces between the stops 21 permit the stops 24 to pass the stops 21 freely in the ordinary traverse of the carriage. It will be noted that the stops 24 are arranged in the same manner and for the same reason. The shaft 23 and the stops 24 carried thereby constitute a graduated stop piece which is mounted on and is movable with the carriage, and is adapted to be adjusted, or

turned to different positions. The series of stops 21 and 24 are each concentrically arranged, being disposed about the axes of their respective shafts 20 and 23 as centers.

It will be evident that many modifications 70 may be made in my tabulating mechanism without departing from my invention.

What I claim as new and desire to secure by Letters Patent, is:—

1. In a typewriting machine and tabulating mechanism, the combination of a carriage, a series of segmentally arranged denomination stops, a rock shaft which extends in the direction of the travel of the carriage, a tabulating stop secured to turn with said 80 rock shaft, and key actuated means for turning the shaft.

2. In a typewriting machine, the combination with a paper holding carriage and a feed mechanism therefor, of a series of stops therefor arranged at different distances from the path of the carriage and adapted to arrest the carriage in different positions, a rotary stop carrier for said stops mounted on an axis parallel with the movement of the carriage, and means operative independently of said feed mechanism for turning said carrier to bring the desired stop into operative position.

3. In a typewriting machine, the combination with a paper-holding carriage of a series 95 of stops therefor arranged at different distances from the path of the carriage and adapted to arrest the carriage in different positions, a rotary stop carrier for said stops on an axis parallel with the carriage and means for turning said carrier to bring the desired stop into operative position, all of said stops being normally out of operative position.

4. In a typewriting machine, the combination of a main frame, a paper holding carriage, a feed mechanism therefor, a series of stops on said frame adapted to arrest said carriage, a rotary carrier for the stops on the said frame, the stops being arranged at different longitudinal positions along said carrier and in different positions around the axis of the carrier, and means operative independently of said feed mechanism for turning the carrier.

5. In a typewriting machine, the combination of a main frame, a paper carriage having a series of column stops, a series of stops normally out of operative position arranged at different distances from the path of the carriage and adapted to arrest the carriage in different positions, a rotary stop carrier for all of said stops mounted on said frame, and a key mechanism for turning said carrier at will to bring the desired stop into operative 120 position, the required turning from any one of said stops to the next being of the same angle or amount.

6. In a typewriting machine and tabulating device, the combination of a power driven 130

carriage, a rock shaft which is carried by the frame of the machine, radially, spirally and segmentally arranged denominational stops which are carried by said rock shaft, a coöperating tabulating stop which is carried by the carriage, and key actuated means which extend to the keyboard of the machine for rocking the shaft to bring any of the denominational stops into the path of the tabulating stop to arrest the carriage at different denominational positions.

7. In a typewriting machine, the combination with a main frame and a paper holding carriage having a part acting as a stop, of a feed mechanism, a series of stops for co-acting with the stop in the carriage, arranged at different distances from the path of the stop on the carriage, and adapted to arrest the carriage in different positions, a rotary carrier for said series of stops mounted on said frame and means independent of said feed mechanism for turning the carrier.

8. In a tabulating attachment for typewriting machines, the combination of a plurality of stops located on the frame of the machine, a graduated contact-piece moving with the paper-carriage and adapted to co-operate with said stops, and a series of tabulator keys coöperating with said contact-piece to set the same to different positions for engagement with said stops.

9. In a key-operated machine, a carriage, a stop which according to the extent of its movement from its normal position will arrest the carriage at different points, and a plurality of keys for imparting movements of different extent to said stop, each of said keys having an independent initial movement during which it does not affect the stop, and a final movement during which it operates the stop, the extent of this final movement being different for each key.

10. In a key-operated machine, a carriage, a tabulating stop which according to the extent of its movement from its normal position will arrest the carriage at different points, a tabulating bar operatively connected with said stop, and a plurality of keys each having an independent initial movement during which it does not move the tabulating bar, and a final movement for actuating said bar and the stop, the extent of this final movement being different for each key.

11. In a typewriting machine and tabulating mechanism, the combination of a carriage, a plurality of concentrically arranged denominational stops, a coöperating tabulating stop, and means for turning the set of denominational stops and the carriage stop one with relation to the other transversely of the travel of the carriage and to different denominational positions.

12. In a typewriting machine and tabulating mechanism, the combination of a carriage, a plurality of segmentally arranged

denominational stops, a coöperating tabulating stop, and key actuated means for turning the set of denominational stops and the carriage stop one with relation to the other transversely of the travel of the carriage and in a plane extending fore and aft of the machine and to different denominational positions.

13. In a typewriting machine and tabulating device, the combination of a power driven carriage, a plurality of denominational stops with intervening spaces between them and which are adapted to be moved to different extents transversely of the travel of the carriage to arrest it at different denominational positions, and a coöperating tabulating stop.

14. In a typewriting and tabulating mechanism, the combination with a carriage, of a column stop, a spiral series of denomination stops, means, including a series of denomination keys, for effecting rotation of said series of denomination stops, and a series of stops for said keys.

15. In a typewriting and tabulating mechanism, the combination of a carriage, of a column stop mounted thereon, a spiral series of denomination stops mounted upon the framework, and means for effecting rotative adjustment of said series of denomination stops.

16. In a typewriting and tabulating mechanism, the combination with a carriage, of a column stop mounted on the carriage, a spiral series of denomination stops journaled upon the framework, and a series of denomination stop keys for variably adjusting said series of stops.

17. In a typewriting machine, the combination with the carriage, of two sets of stops, and means for adjusting both of said sets of stops to arrest the carriage at a point determined by the adjustments of both sets.

18. In a typewriting machine, the combination with the carriage of two stop devices, each adjustable to different positions; and keys for adjusting said stop devices to arrest the carriage at a point determined by both adjustments.

19. In a typewriting machine, the combination with the carriage, of two spirally arranged sets of stops, and means for turning said sets of stops to bring one stop of each set to operative position to arrest the carriage at a position determined by both stops.

20. In a typewriting machine, the combination with the carriage, of a spirally arranged set of stops which moves with the carriage; a second spirally arranged set of stops which does not move with the carriage; and means for turning said sets of stops to bring any selected stop of one set into position to engage any selected stop of the other set.

21. In a typewriting machine, the combination with the carriage, of two sets of stepped stops, and means for causing any se-

lected stop of one set to coöperate with any selected stop of the other set to arrest the carriage.

22. In a typewriting machine, the combination of a carriage, a graduated stop device mounted on said carriage, a keyboard mounted on said carriage and controlling said stop device, and a stop coöperating with said stop device to arrest the carriage.

10 23. In a typewriting machine, the combination with the carriage, of two coöperating series of stops for arresting said carriage, and separate keyboards for controlling said series of stops.

15 24. In a typewriting machine, the combination with the carriage, of a rock shaft mounted on said carriage; a series of stops controlled by said rock shaft; a series of keys mounted on said carriage; and means whereby said keys turn said rock shaft different distances.

25 25. In a typewriting machine, the combination with the carriage, of a rock shaft mounted on said carriage; a series of stops carried by said rock shaft; a series of keys mounted on said carriage; a plate which is rocked different distances by the different keys of the series; and gearing whereby said plate controls said rock shaft.

30 26. In a typewriting machine, the combination with the carriage, of a rock shaft mounted on the main frame; a series of stops controlled by said rock shaft; a second rock shaft, geared to said first mentioned rock shaft; a segmental gear controlling said second rock shaft; and a keyboard mechanism for controlling said segmental gear.

35 27. In a tabulating device for typewriting machines, the combination of a series of stops corresponding to single units of movement; a second series of stops corresponding to groups of units; and means for rendering operative one stop of each series whereby the typewriter carriage may be stopped in any desired position within the limit of its travel.

40 28. In a typewriting machine, the combination with the carriage, of a series of stops corresponding to single units of movement; a second series of stops corresponding to groups of units, one of said series of stops being mounted on the frame and the other on the carriage; and means for selecting a stop of each series and bringing them into operative relation to locate the carriage at any desired point.

45 29. In a typewriting machine, the combination of a shaft longitudinally arranged on the typewriter carriage and provided with a spirally arranged series of stops; a second shaft mounted on the typewriter frame in parallel relation to the first shaft and having also a spirally arranged series of stops; and means for setting said shafts to bring any

desired stop of the latter shaft into the path 65 of any desired stop on the shaft carried by the carriage.

30. In a tabulating device for typewriting machines, the combination of a series of stops corresponding to groups of units on the typewriter scale; and a keyboard having keys adapted to select said stops respectively, in combination with a second series of stops corresponding to units of said typewriter scale; and a keyboard having keys adapted 75 to select the stops of said second series respectively.

31. In a tabulating device for typewriters, the combination of two parallel shafts each having a spirally arranged series of stops, 80 and a keyboard for each shaft provided with keys and connections for turning said shaft, one of said shafts being mounted on the typewriter carriage and the other being mounted on the machine frame.

85 32. In a typewriting machine, the combination of a carriage, and tabulating mechanism including key controlled selecting means operable at will to arrest the carriage at any letter space position in its travel, said position being determined by said key controlled selecting means.

90 33. In a typewriting machine, the combination of a carriage, and tabulating mechanism including key controlled selecting means 95 operable at will for arresting the carriage at any desired denominational position in any desired column during a single run of the carriage, said position being determined by said key controlled selecting means.

95 34. In a typewriting machine, the combination of a carriage, a series of denominational stops, a series of column stops, and key controlled selecting means for bringing any desired denominational stop into coöoperative 105 relation with any desired column stop to arrest the carriage at any desired denominational position in any desired column during a single run of the carriage, said position being determined by said key controlled selecting 110 means.

105 35. In a tabulating attachment for typewriting machines, the combination with the transversely movable paper carriage, of a 115 rock shaft, a stop mounted upon said shaft and adapted to coöperate with the paper carriage to arrest the latter at different denominational positions, and a plurality of tabulator keys and connections for turning the rock shaft to adjust the stop to arrest the paper carriage at the desired denominational position.

120 36. In a tabulating device for typewriting machines, the combination of a series of stops, the spacing between which corresponds to 125 single units of movement, a second series of stops, the spacing between which corresponds to the spacing of the entire series of

the first mentioned stops, and means operable at will for rendering operative one stop of each series.

37. In a tabulating device for typewriting machines, the combination of a series of denominational stops situated a single letter space distance apart, a series of column stops fixed ten letter space distances apart, and means for bringing said stops into coöperative relation.

38. In a tabulating device for typewriting machines, the combination of a series of denominational stops situated a single letter space distance apart, a series of column stops

situated ten letter space distances apart, and means operable at will for rendering operative any one stop of each series, whereby the carriage may be arrested at any letter space position in the travel of the carriage.

Signed at the borough of Manhattan, city of New York, in the county of New York, and State of New York, this 7th day of Sept. A. D. 1904.
